HYPODERMIC SYRINGE FOR FILLING A ROOT CANAL OF A TOOTH OR THE LIKE

Israel Katz, 150 Howe St., Natick, Mass.

Filed Jan. 10, 1963, Ser. No. 73,135

Term of patent 14 years

(Cl. D24—1)

FIGURE 1 is a view in perspective of the hypodermic syringe for filling a root canal of a tooth or the like showing my new design.

FIGURE 2 is a front elevation thereof and

FIGURE 3 is a front elevation thereof with portions omitted for ease of illustration.

The dominant features of my design reside in the full line portions.

I claim:

The ornamental design for a hypodermic syringe for filling a root canal of a tooth or the like, substantially as shown and described.
